Fig. 3

FIG. 1

FIG. 4

FIG. 5

FIG. 8

FIG. 6

FIG. 1 is a perspective view of one embodiment of a kite string holder embodying our new design;

FIG. 2 is a bottom plan view of the holder of FIG. 1;

FIG. 3 is a side elevational view thereof;

FIG. 4 is a modified form of a kite string holder;

FIG. 5 is a side elevational view of the modification of FIG. 4;

FIG. 6 is a further modified form of a kite string holder embodying our new design;

FIG. 7 is a cross-sectional view of the frame portion of FIG. 6, taken along section line 7—7; and

FIG. 8 is a cross-sectional view of the frame portion of FIG. 2, taken along section line 8—8.

We claim:

The ornamental design for a kite string holder, substantially as shown and described.
